MACHINE FOR FORMING SPIRAL HEAT EXCHANGE COILS

Oren Bishop, Somerset Center, and Charles C. Miller, Addison, Mich., assignors to Addison Products Company, Addison, Mich.

Application February 26, 1952, Serial No. 273,414

5 Claims. (Cl. 242—82)

This invention relates to a machine for forming longitudinally finned tubing into spiral evaporator coils, and wherein provision is made for uniformly spacing and locking the successive convolutions of the coil by means of a pivoted entrance guide box structure which coordinates the feed of the tubing and the spacing wires, and wherein provision is also made for rapidly connecting or disconnecting the inner end of the coil to a rotatable forming mandrel.

The principles of the invention, and the advantages to be derived from the practice thereof, will be apparent from the following description of a practical embodiment, illustrated in the accompanying drawings, wherein:

Fig. 1 is a plan view, with a finished coil shown on the top of the table;

Fig. 2 is a front elevation, the work being shown in position at the start of a forming operation;

Fig. 3 is an enlarged view of the mandrel and guide box, the latter being shown in section;

Fig. 4 is an enlarged view from the right of Fig. 3, with portions broken away;

Fig. 5 is an additionally enlarged sectional view, taken substantially on the line 5—5 of Fig. 3;

Fig. 6 is an enlarged view, partly in section, of a latch and operating mechanism therefor;

Fig. 7 is a view of the inner end of the latch operating handle;

Fig. 8 is a view looking into the open end of the latch operating mechanism, showing the latch engaged in full lines, and retracted in dotted lines;

Fig. 9 is a perspective of the latch element; and

Fig. 10 is an enlarged side elevation of a hold down.

The machine herein specifically illustrated and described is adapted to make finned spiral coils useful as heat inter-changers, such as an evaporator for a refrigeration machine, although the machine is not limited to the fabrication of this article alone. Referring to Figs. 1, 2, and 5, there is shown in end view, side elevation, and section, the nature of such finned coil. It comprises a length, or two parallel connected lengths, of tubing T having a relatively flat tube portion 21 with integral longitudinal fins 22 along the narrow dimension, and these fins have been corrugated lengthwise into a generally sinusoidal configuration, to provide crests 23, 24, rising above the flat surfaces of the tubing. Additionally, the crests of the corrugations are reversely depressed adjacent their outer margins, to provide saddles 25. After the stock has been so formed in conveniently continuous lengths, it is operated upon by the present machine, which wraps the tubing into spiral form, and simultaneously introduces spacing wires 26 lengthwise of the tubing, and in the saddles of the fins, where they serve various purposes, including the uniform spacing of the convolutions, and their retention against axial or radial displacement.

For a detailed description of this particular coil, reference is made to the application of Stanley H. Morse, Serial No. 273,409, filed February 26, 1952, now Patent 2,692,119, issued October 19, 1954.

Referring primarily to Figs. 1 and 2, the machine comprises a table 31 having a shelf 32 on which are mounted a driving motor 33 having a double ended shaft to one end of which is connected a magnetic brake 34, the details of which form no part of the present invention. The motor may be manually controlled from a switch box 35 on the top 36 of the table, the indicated electrical connections being made in a relay box 37 conveniently posi-

tioned on the shelf 32. The opposite end of the motor shaft is provided with a sprocket over which is disposed a chain 38 extending upwardly through a slot 39 in the top 36, and over the input sprocket 41 (Fig. 4) of a speed reduction unit 42 of any desired type.

The output shaft 43 of the reduction unit 42 extends through a bearing pedestal 44, and it has secured to its end a collar 45 (Fig. 4), to which is welded or otherwise connected a circular backing plate 46, on which in turn is mounted a slotted and generally spiral mandrel 47. A bifurcated mounting bracket 48 is positioned on the left hand side of the table top 35, to support spools 49 of spacing wire 26, and also to support an entrance guide box structure, generally designated by the reference numeral 51. The structure 51 is generally in the form of a rectangular box having open ends, and it is pivotally mounted between the legs of the bracket 48 by a block 52, welded to the under left hand portion of the box 51, from which extend trunnions 53 entering suitable bearing apertures in the bracket 48. (See also Figs. 3 and 5). The length of the box is such that its right hand end abuts the rim of the disc 46 when the box opening is substantially tangent to the mandrel 47, which is the starting position.

As best shown in Figs. 3 and 5, the guide box 51 comprises a bottom 54 formed with a slot 55 at its forward end, upright side walls 56 and 57, and a hinged top 58 which may be secured in closed position by a hasp 59. Two tracks 61 and 62 are mounted on the upper side of the bottom 54, and they are so located with respect to the dimensions of the tubing T as to abut the surface of the tube portion 21, when the work is laid flat in the box. Concurrently, the outer edges of the fins 22 abut the sides of the box and each other—the present guide being adapted to receive two tube lengths to make a double coil.

A switch 63 is secured to the bottom 54, and it is provided with a pivoted actuating lever 64 having a roller 65 at its end, which projects through the slot 55 and above an interrupted portion of the track 62. When a length of tubing T is laid in the box on the track 62, and the cover is closed, the roller 65 is depressed to close a circuit taken through the switch 63, a line 66, and relay box 37, which conditions the switch 35 for manual operation. When the tubing T is removed, as by moving the trailing end thereof out of the box and onto the mandrel 47, the lever 64 is spring elevated to open the circuit through the switch 63, thereby opening the motor circuit and applying the brake 34, and overriding the action of the manual switch 35. Hence, at the conclusion of the winding operation, the machine is automatically stopped.

The box top or lid 58 is formed at its forward end with four slots 67 having curved ends, each of which is so positioned as to be directly over the line of saddles 25 on either side of the tubing T. The wires 26 are threaded into the slots and are brought forward toward the mandrel 47, and are hooked or otherwise anchored to the ends of the fins 22, as is clearly shown in Fig. 3. When the lid 58 is closed and latched, the wires 26 are pressed into the line of saddles, to hold the tubing T firmly on the tracks 61 and 62. Stated otherwise, the guide box 51 is so dimensioned with respect to the work that, when the work is in position, it is drawn through the guide structure against enough frictional resistance to insure the positioning of the wires 26 in the saddles 25. The parts of the final assembly of the coil are thus fitted properly together before reaching the mandrel, and additional special drags on the reels 49, or on the tubing T, are thereby rendered unnecessary.

As best shown in Fig. 3, the mandrel 47 consists of a piece of metal wrapped initially into a generally cylindrical form, but with the edges spaced radially to provide an entrance slot 71, and thus to conform the shape of the mandrel more to that of a spiral. The forward end or ends of the tubing T may be inserted through the slot 71 to be secured within the mandrel, so that, as the mandrel is rotated, the work will be pulled through the box 51, and wrapped on itself to form a spiral coil. In the embodiment herein specifically described, the work is shown as comprising two parallel lengths of tubing T, the forward ends of which are connected by a return bend B, from which the fin stock has been removed. This is the part

of the work which is positioned inside of the mandrel, the balance, of course, being wound around the outside.

The work securing mechanism comprises a latch 72 (Fig. 9) pivotally mounted on a bearing 73 disposed on the inner periphery of the mandrel 47 which is spaced from the slot 71. The outer end of the latch 72 is formed with a hook or finger 74, which may be engaged in the bight of the return bend B, and with a tapped aperture 75. One end of an operating link 76 is connected to the outer end of the latch 72 by a screw 77. There is also mounted within the mandrel 47, in spaced relation to the slot 71 and bearing 73, an oscillatable stud 78 which is mounted in a socket drilled in the back plate 46. The stud 78 is pinned to a concentric bushing 81 at its outer end, and the bushing in turn is axially drilled to provide a pocket 82, in which is secured one end of a rod 83 by means of a set screw 84. The outer end of the rod 83 is transversely drilled to receive a rod 85, by means of which the assembly may be rotated.

The bushing 81 is eccentrically drilled and tapped at the base of the pocket 82, and it is also here formed with a circumferential slot 86. The opposite end of the link 76 is positioned through the slot, and it is pivotally secured within the pocket 82 by a screw 87. The slot is of such arcuate length that the bushing 81 and attached rods 78 and 83 may be rotated about 180° before the opposite edges of the link 76 abut the ends of the slot 86. Such rotation moves the link 76 toward or away from the mandrel slot 71, and thus causes the latch 72 to swing toward or away from the return bend B of the work.

It will be understood that, when the forward end of the tubing T is positioned through the slot 71 and is secured by the latching mechanism, and the guide box cover 58 is closed, the switch 63 will be energized, and the mandrel 47 and disc 46 may then be rotated under the control of the switch 35. This motion draws the tubing T and wires 26 through the box 51 against the described resistance, and forms the relatively flat length of stock into a spiral coil, the diameter of which progressively increases. The incoming length or lengths of tubing, however, are automatically maintained substantially tangent to the coil at all times, as the guide box 51 pivots upwardly on its trunnions 53. This condition is indicated by the broken lines in Fig. 3.

It is advantageous, particularly at the end of the winding operation, or at times when it may be desired to stop the machine before the coil is completely formed, to provide means for holding the convolutions against possible back lash or slippage. For this purpose, there is provided a spring actuated hold down, illustrated in Figs. 3 and 10. The bearing pedestal 44 is drilled at its upper end to receive a forwardly extending rod 91 which is threaded at its end to receive a retaining nut 92. A spacing sleeve 93 is positioned over the rod 91, and against its outer end is a collar 94, having plates 95 welded to its ends. The opposite ends of the plates are drilled to receive a pin 96 carrying a roller 97. A second roller assembly 98 is positioned on the rod 91, and between the two is a wrap-around torsion spring 99, secured to the rod 91 by a pin 101, and having its ends 102 and 103 connected to the adjacent plates 95 of the two roller units. A nut 104 on the outer end of the rod 91 retains the parts in position.

At the beginning of a winding operation, the rollers 97 rest on the mandrel 47, and, as the work is coiled, they bear on the flat surfaces of the tubes 21, and are swung counterclockwise, as shown by the broken lines in Fig. 3. Although the work is under tension, the pressure exerted by the rollers aids in forestalling any tendencies for misalignments. As previously noted, when the trailing end of the work passes the rollers 65 of the solenoid switch 63, the machine is automatically stopped. The hold down levers then resist any unwinding tendency while the operator snips the wires 26 below the end of the outermost convolution, works the short tangential end into position, and secures the assembly by suitable means, such as screws sunk through the fins.

It is believed that the foregoing description adequately explains the nature and mode of operation, and that a repetition is therefore unnecessary. It will be seen that the work is properly fed to the winding mandrel, with the edge of one fin abutting the backing plate 46 to assure the formation of a coil whose faces lie in substantially parallel planes. After the coil has been formed, the operator re-

leases the latch 72, and the assembly can then be pulled forward to remove it from the machine.

It will accordingly be seen that the present invention provides a simple and inexpensive machine for forming spiral coils, and it is particularly adapted to making heat exchange coils from longitudinally finned tubing, and wherein the convolutions are positively spaced. While the invention has been described with reference to a specific embodiment, it will be obvious that various changes and modifications may be made without departure from its principles. Accordingly, it is intended that the invention be accorded a scope commensurate with that expressed in the following claims.

We claim:

1. A machine for forming spiral heat exchange coils comprising a rotatable mandrel formed as a convolution of a spiral and having the edges of the convolution radially spaced, detachable latch means within the mandrel for gripping the leading end of a workpiece, a guide

20 structure comprising a box having a bottom, sides, top and open ends, a work supporting track positioned within the box on the bottom thereof and between the sides, the width of the box being greater than its inside height, a supporting bracket for pivotally mounting the box adjacent one open end with the other end facing toward the mandrel, means for initially positioning the track of the box approximately tangent to the surface of the mandrel, the top of the box being formed with guide openings on either side of the track of sufficient size to receive 25 spacing wires to be coiled with a workpiece fed through the open ends of the guide box.

2. A machine for forming spiral heat exchange coils comprising a mandrel formed as a convolution of a spiral and having the edges thereof radially spaced, a bearing for

35 mounting the mandrel for rotation about a horizontal axis, latch means within the mandrel and rotatable therewith for securing the end of a workpiece positioned therein between the edges of said convolution, a guide structure pivotally mounted adjacent the mandrel for rotation

40 about an axis parallel to the axis of rotation of the mandrel, said guide structure comprising a box having top, bottom and side walls and open ends, the axis of rotation of said guide structure being positioned adjacent one open end, the opposite open end being positioned adjacent the mandrel and adapted to be substantially tangentially aligned therewith, a longitudinal track in the box between the sides thereof, and parallel slots formed in the box adjacent said opposite open end and on either side of the track.

50 3. A machine as set forth in claim 2, wherein the guide box track is interrupted adjacent said opposite open end, the bottom of the box is formed with a slot below the interrupted portion of the track, and a depressible control lever is mounted on the bottom of the box to extend 55 through said slot and above the interrupted portion of the track.

4. A machine as set forth in claim 2, further characterized in that the latch is pivotally mounted at one end on the inner surface of the mandrel at a point spaced 60 from the entrance opening, and the latch actuating mechanism comprises a rotatable bushing mounted on the backing plate at a point spaced from said entrance opening and the pivoted end of the latch, said bushing being formed with a circumferential slot, and a link having one end extending through said circumferential slot pivotally mounted within the bushing and its opposite end pivotally connected to the latch.

5. A machine as set forth in claim 2, wherein the bearing means for the mandrel comprises an upright pedestal having a horizontal supporting rod projecting therefrom above the mandrel, a hold down arm pivotally mounted on the rod, and a spring connected to the rod and arm to urge the arm toward the mandrel and a coil formed thereon.
